US00D800722S

(12) **United States Design Patent** (10) **Patent No.:** **US D800,722 S**
(45) **Date of Patent:** **** Oct. 24, 2017**

(54) **WEARABLE DEVICE**

(71) Applicant: **SAMSUNG ELECTRONICS CO., LTD.**, Suwon-si (KR)

(72) Inventors: **Myung-Kyu Kim**, Seoul (KR); **Yong-Seok Bang**, Yongin-si (KR)

(73) Assignee: **SAMSUNG ELECTRONICS CO., LTD.**, Gyeonggi-Do (KR)

(**) Term: **15 Years**

(21) Appl. No.: **29/558,334**

(22) Filed: **Mar. 16, 2016**

(30) **Foreign Application Priority Data**

Nov. 27, 2015 (KR) 30-2015-0060250

(51) **LOC (10) Cl.** **14-02**

(52) **U.S. Cl.**

(57) **CLAIM**

The ornamental design for a wearable device, as shown and described.

DESCRIPTION

FIG. 1 is a front perspective view of a wearable device, showing our design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines illustrating portions of the wearable device form no part of the claimed design.

1 Claim, 7 Drawing Sheets
